DRAWING AND SPOOLING MECHANISM AND METHOD.

Application filed July 5, 1923. Serial No. 649,495.

This invention relates particularly to a gear, so that the carrier will be rotated through a suitable angle at the end of each spooling operation. 5
Method adapted to the continuous drawing and spooling or reeling of a strand of material such as wire, and to mechanism where-
by said method may be conveniently practiced. The mechanism is particularly adapted to the purpose of drawing and spooling wire of the larger sizes, and especially where the wire is spooled upon a comparatively 10 large sized spool.

The mechanism is suitable, also, for recoiling, or respooling wire or the like. It is well adapted for respooling wire when the wire is drawn through an annealing furnace, 15 or is given a coating, such as a galvanizing coating, or a coat of enamel. The mechanism enables the coiling or spooling operation to be performed as a continuous, or non-stop, operation.

20 The mechanism may be used to divide a large coil or spool of wire into several smaller coils or spools of predetermined length of wire per spool. The length may be varied, as desired.

25 The improved mechanism is shown in the preferred embodiment in the accompanying drawings. In the illustration given, the wire is drawn through a finishing die by means of a self-discharging capstan, from which 30 the wire passes to the spooling mechanism proper. Generally stated, the spooling mechanism shown comprises a carrier which is automatically moved by a step-by-step movement at suitable intervals, depending upon the amount of wire to be wound upon 35 each spool; a plurality of spindles journaled in the carrier and having projecting ends upon which the spools are demountably carried; a loose gear upon each spindle and a 40 suitable clutch associated therewith, said gears turning idly on their spindles, except that as the spooling operation is performed by each spindle the gear on the spindle is clutched to the spindle so as to cause the spindle to turn; a suitably operated central gear which meshes with the spindle-gears and drives them continuously; a carrier actuating gear which meshes with a large gear secured to the carrier and through the 45 medium of which the carrier is rotated periodically a suitable distance to remove the loaded spool from the winding position and bring a fresh spool into the winding position; and control mechanism adapted to control the operation of the carrier actuating

50 Associated with each spindle is a wire distributing device for properly distributing the wire on the corresponding spool as it is being wound thereon. The distributing device normally has a traverse equal to the distance between the flanges of the spool. After 55 each spooling operation, however, the distributing device is given an extra movement by means of a suitable cam which deflects the wire, or carries it over the flange of the spool and in the path of grippers with which the face plates on the spindles are provided, 60 so that the wire will be engaged by the grippers, and practically simultaneously therewith a knife or shearing device operates to sever the wire at a point between the gripper 65 associated with the loaded spool and the gripper associated with the fresh spool which 70 is to be wound.

In the accompanying drawings—

Fig. 1 is a broken elevational view of the improved mechanism, showing the side of 80 the machine where the spools are disposed, the spools being shown as four in number; Fig. 2, a broken sectional view on an enlarged scale, taken as indicated at line 2—2 of Fig. 1, the view showing one of the spools 85 in elevation and showing in section the spindle-gear and its associated clutch device; Fig. 3, an enlarged broken sectional view taken as indicated at line 3—3 of Fig. 1, this view showing one of the distributing devices 90 and a part of the control mechanism mentioned above; Fig. 4, a broken elevational view showing the upper right hand corner portion of the rear end of the main frame and a part of the control mechanism mounted 95 thereon, this view corresponding with the portion broken away in Fig. 10, but being on an enlarged scale; Fig. 5, a broken plan view somewhat in the nature of a development, partly in section, the view being taken 100 approximately as indicated at line 5—5 of Figs. 1 and 3, it being noted, however, that the spool-carrier has been rotated from the position shown in Fig. 1 to bring the distributing device associated with the right 105 hand spool shown in Fig. 5 to the position indicated by the line "a" in Fig. 1; Fig. 6, a fragmentary view of the face plate of one of the spindles, showing one of the associated wire grippers; Fig. 7, a broken sectional 110

- view taken as indicated at line 7—7 of Fig. 6, the wire not being shown in section, however; Fig. 8, an enlarged sectional view of a spool carrying slide which is employed for removing the loaded spools, the section being taken as indicated at line 8—8 of Fig. 1 and one of the spools being shown brokenly, mounted on the slide, ready for removal from the spindle; Fig. 9, an enlarged broken 5 sectional view showing the main central drive shaft of the machine and showing also the bevel-gears for communicating motion to the self-discharging drawing capstan which appears at the left upper corner of 10 Fig. 1; Fig. 10, a rear end elevational view (partly in section) of the machine; Fig. 11, a sectional view of the self-discharging drawing capstan, the section being taken as indicated at line 11—11 of Fig. 1; and Fig. 15 20 25 30 35 40 45 50 55 60 65
- Fig. 12, an enlarged detailed sectional view taken as indicated at line 12—12 of Fig. 4, the detail showing the oscillating arm and pawl employed in connection with a ratchet device which forms a part of the control mechanism of the machine, the variation in the amount of wire to be wound upon the spools being controlled by means of an adjustable segment (cam) associated with the ratchet wheel and cooperating with the pawl, as illustrated in Fig. 4.
- In the construction illustrated, A represents a self-discharging wire drawing capstan having associated therewith a presser device A', which serves to press the convolutions of wire which encircle the drawing capstan by a sort of clamping action against the capstan; A², a die through which the wire is drawn upon the capstan, which die may constitute the finishing die of a wire drawing machine, if desired; B, a main frame for the spooling mechanism proper, this frame being preferably in form of a housing for the carrier and affording a front end wall B', a rear end wall B², a top wall B³, and a reverse-side wall B⁴; B⁵, a supplemental housing member mounted on the top of the main frame; C, a rotatable carrier comprising a front side-wall C' adjacent to which the spools are mounted, a circumferential wall C², and an inturned flange C³ disposed opposite the wall C'; D, E, F and G, a series of spindles journaled in the carrier C near the periphery thereof, each spindle being equipped with a loose spindle-gear H and an associated clutch device H'; D', E', F' and G' face plates formed integrally with the respective spindles and disposed outside the carrier wall C'; D², E², F² and G², spools mounted on the respective spindles; I, J, K and L, wire distributing devices associated respectively with the spools D², E², F² and G²; M, a central drive shaft journaled in the wall B⁴ of the main frame, equipped at one end with a gear M' which meshes with the spindle-gears H and

having a projecting end equipped with a drive gear M² through the medium of which power may be communicated to the machine from any suitable source; N, a bevel-gear fixed on the outer end of the shaft M and serving to communicate motion through a shaft N' to a bevel-gear N² fixed on the shaft of the self-discharging capstan A; P, a large annular gear fixedly secured to the flange C³ of the carrier C; R, control mechanism serving to control the movements of the carrier C, this mechanism also including a device for actuating the wire distributors in their normal operation; S, a cam serving to give to the distributors, seriatim, an extra movement to deflect the wire and effect severance thereof, the cam S being carried by the top wall B³ of the housing B; and T, a large segmental, or interrupted cam which is adapted to prevent clutching of the spindles to the spindle-gears, except through that portion of the circle where the interruption of the cam occurs. It may be added here that the spindle D is in the winding position and therefore is clutched to its actuating gear. 75 80 85 90 95 100 105 110 115 120 125 130

The self-discharging capstan, in the form shown, comprises a suitably journaled shaft 1 and a grooved disk 2, about which the wire 3 takes several turns. The presser device A', comprises, in the form shown, radial arms 4, carried by a segmental spring 5, the outer ends of the arms being equipped with pressure-rollers 6, which bear yieldingly against the convolutions of the wire 3. The spindle 6^a of one of the rollers bears against a projection 7 of the frame member 7^a in which the shaft 1 of the capstan is journaled. 110

The frame or housing B may be of any suitable form and construction, the construction described above being well adapted to the purpose. The frame is provided with internal annular bearings 8 and 9, in which the carrier C is journaled. The bearing 8 presents a beveled surface, which is engaged by a corresponding bevel on a flange 8^a of the wall C' of the carrier. Segmental retainer plates 10, suitably secured to the housing, as by means of screws 10^a, serve to retain the carrier properly in its bearings. 115 120 125 130

The carrier C is rotated in the bearings just described by means of the large annular gear P, which is actuated by a gear which forms a part of the control device R. 130

As has been indicated, the spindles D, E, F and G are journaled in the carrier, the carrier being provided with suitable journal bearings 11 and 12 for such purpose, as shown in Fig. 2. The spindle and clutch devices are of the same construction, and may be explained with reference to Fig. 2. In the illustration given, each spindle is equipped with a fixed disk or flange 13 and a movable clamping plate 14, the gear being confined between these plates. The plate 14 is pressed by means of springs 15, the tension of which may be adjusted by means of nuts 16. The gear and the plates referred to are mounted on a sleeve 17 which is journaled freely on the spindle. The sleeve is provided with an internal key-way 18, adapted to receive a key 19, which is secured to a plunger 20, which operates through a bore in the spindle. The key is moved to the locking position by means of a spring 21, which is confined in the bore. The other end of the plunger 20 is equipped with a ball or anti-friction member 22, which is adapted to travel on the cam T. The cam is provided with suitably beveled or rounded ends. While the ball at the end of the plunger engages the cam while the carrier is being rotated, the plunger is retracted against the pressure of the spring 21 and releases the clutch. When the ball rides off the end of the cam, the clutch is allowed to operate to throw the spindle into operation, that is, to cause the spindle to rotate with the gear H. It will be noted that the arrangement of the cam T is such as to permit the fresh spool G² to be turned on its axis during the time while it is being carried from the position shown in Fig. 1 to the normal winding position occupied by the spool D², as shown in Fig. 1. This enables the wire to be gripped by one of the grippers on the face plate associated with the spool G² before the wire is severed; and it may be remarked, also, that the final end of the wire wound on the spool D² is gripped by one of the grippers of the associated face plate D', thus preventing the wire from unwinding from the spool.

The cam T is, of course, stationary, being carried by the wall-plate B⁴ of the housing. The distributing devices I, J, K, and L are of the same construction, and may be explained with reference to Fig. 3. There, the device I is shown as comprising a plunger, or slide-rod which operates through a bearing 24^b in the front side plate C' of the carrier; a guide member 23^a, secured to the inner end of the plunger and provided with a bore which is adapted to slide on a guide rod 24 mounted in the carrier; an arm 23^b rigidly secured to the outer end of the plunger 23 and equipped with a knife or shear 23^c; and a pair of guide fingers 25, adapted to receive the wire 3 in the slot be-

tween them. The arm 23^a is provided with a suitable bore which receives a ball 26 and a spring 27, the ball 26 being pressed against the guide rod 24, and adapted to partially enter a recess 24^a with which the guide rod 70 is provided. Thus, the distributor is releasably locked at one end of its traverse, the purpose being to hold the distributor in the position shown in Fig. 3 when the distributor is not being actuated for any purpose.

The arm 23^a is equipped at its outer end with a cam stud 28, which is adapted to be actuated by a slide mounted at the upper portion of the main housing, said slide being 80 actuated by a cam wheel which forms a part of the control mechanism R. The distributors J, K and L are of the same construction as the distributor I, and they are actuated in the same manner. The distributors 85 are brought, seriatim, within the range of operation of the slide just mentioned, it being understood that each distributor is actuated in its turn while the associated spool 90 is being filled with wire.

The gear wheel M' meshes with the spindle-gears H on the several spindles, as will be best understood from Figs. 1 and 2.

The control mechanism R for regulating the number of turns of wire per spool and the connection between said control mechanism and the slide actuating the wire distributors will be best understood from Figs. 1, 3, 4, 5, 9 and 10. The mechanism comprises a pinion or sprocket wheel 29 (Fig. 9), secured on the shaft M; a counter-shaft 30 (Figs. 1 and 10) journaled in the upper portion of the frame member B⁴ and equipped at its inner end with a fixedly secured gear 30^a, which meshes with the large 95 carrier actuating gear P; a pair of pinions or sprocket wheels 31 and 32 (Fig. 10) formed integrally with a sleeve 33, which is journaled on the outer end of the counter-shaft 30; a shaft 34 journaled in the top 100 frame member B⁵ and equipped at its inner end with a bevel-gear 34^a and at its outer end with a pinion or sprocket wheel 34^b; a sprocket chain or silent-drive chain 35 connecting the gears 29 and 31; a similar chain 105 36, connecting the gears 32 and 34^b; a short vertical shaft 37 journaled in the frame member B⁵ and equipped with a large bevel-gear 37^a, which meshes with the bevel pinion 34^a, and equipped also with a cam wheel, or segment 37^b which is provided at its lower side with a cam groove 37^c and at its upper side with a cam lug 37^d; a distributor actuating slide 38, which moves in a guide slot 39, with which the frame portion B³ is provided and which has its upper portion provided with a cam stud 38^a engaging in the cam groove 37^c and which has its lower portion provided with a fork 38^b, which affords a slot 38^c adapted to receive the cam stud 28 110

115

120

125

130

of each distributor, in turn; a rock shaft 40, journaled in the frame member B⁵ and having a horizontal arm 40^a, adapted to be actuated by the cam 37^a and having a depending arm 40^b (Fig. 4); a clutch device adapted to connect the counter-shaft 30 to the sleeve 33, said clutch device comprising (Figs. 4 and 10) a key 41, adapted to slide in the transverse slot in the shaft 30 and to engage a groove or recess 41^a with which the inner end of the sleeve 33 is provided, the sliding key 41 being thrown to the engaging position by a spring 41^a confined in a bore in the shaft 30; a vertical link 42 provided at its lower end with a cam 42^a, adapted to restrain or hold the key 41 out of the engaging position (Figs. 1 and 4); a rock-lever 43 supported on a pivot 43^a, said lever being disposed at the far side of the machine as illustrated in Fig. 1, the front end of the lever being pivotally connected with the upper end of the link 42 by means of a pivot 44; a horizontally movable slide 45, supported on guide studs 46, which project from the rear end wall B² of the main frame, said slide 45 having an end portion which projects past the reverse side of the machine and which is provided with an inclined cam slot 45^a which engages a cam stud 47 on the rear end of the lever 43; a spring 48 serving to move the slide 45 in one direction; a fixed stud or shaft 49 which projects from the rear end wall B² of the main frame; a ratchet wheel 50 journaled on the stud 49; an arm 51 adjustably secured on the stud 49, said arm having a split inner end and a set screw 51^a for adjusting the arm angularly in any desired position, and the arm being provided at its outer end with a cam or shoe 51^b; a rock-lever 52 having one arm connected with a spring 52^a and another arm carrying a pivot 52^b, and provided also with a projecting lug 52^c; a pawl 53 journaled on the pivot 52^b and engaging the ratchet wheel, said pawl being adapted to ride, during a portion of its stroke, on the shoe 51^b; a link 54 connecting the pivot 52^b with the rock-arm 40^b; a slide-actuating link 55, connected by a pivot 55^a with the slide 45, and equipped with a block 55^b which affords a cam 55^c and a shoulder 55^d; a rock-lever 56 supported on a pivot 56^a and having its upper end provided with a cam stud 56^b, which normally supports the link 55 in the raised position shown in Fig. 4; and a cam stud 57 mounted on the ratchet wheel and co-acting with a cam stud 57^a with which the lower end of the rock-lever 56 is provided.

The arm 51 is adjustable to enable the position of the shoe 51^b to be varied, so that the pawl 53 will ride idly over the shoe a greater or less distance, depending upon the adjustment, thus varying the movement of the ratchet wheel at will. This arrangement enables the number of turns of wire

wound upon a spool to be varied, as desired. When the rock-lever 56 is withdrawn from the position in which it supports the slide-actuating link 55, this enables the point 52^c of the rock member 52 to engage the shoulder 55^d and thus actuate the slide 45 through the medium of the link 55. When the slide 45 is moved to the left, viewed in Fig. 4, the rear end of the lever 43 is depressed, thereby lifting the link 42 and permitting the clutch member 41 to engage the clutch member 41^a. Thus, the counter-shaft 30 is clutched to the sleeve 33 and thus caused to rotate, so as to turn the carrier-actuating gear 30^a. This action takes place periodically at the completion of the filling of the spools, in turn. The cam 42^a then operates to disengage the clutch-member 41 from the recess 33 in the sleeve 30.

Normally, the wire distributor while in operation has an amplitude of movement corresponding with the movement of the slide 38 shown in Fig. 3. However, when the carrier rotates to bring a fresh spool into the normal filling position, the cam stud 28 of the distributor slide moves into a cam slot 58 of the cam S, as shown in Fig. 5. That is, the cam stud 28^a passes out of the slot 38^a of the fork 38^b and enters the cam slot 58. This slot is so formed that it will 95 retract the distributor further than shown in Fig. 3. This has been referred to as the extra movement of the distributor which serves to deflect the wire and bring it within the range of the grippers with which the 100 face plates of the spindles are provided. To effect severance of the wire, the main frame is provided with an anvil or lug 59, which co-acts with the shear 23^c (Figs. 3 and 5).

The face plate of each spindle is provided with a suitable number of wire-grippers 60. These grippers project from the face plate, as shown in detail in Fig. 6, the gripper forming an acute angle 60^a with the outer face of the face plate. Thus, the wire 3 is adapted to be gripped between the gripper and the corner formed by the periphery of the face plate. This is illustrated in an exaggerated manner in Fig. 7. As has been stated, the severance of the wire occurs practically simultaneously with the gripping. Suitable means for adjusting the knife 23^c are provided. As illustrated in Fig. 5, the knife is mounted in a slot in the arm 23^b, the metal of the arm being split and provided 115 with a set screw 61.

Any suitable means may be provided for effecting removal of the spools. Referring to Figs. 1 and 10, 62 represents a slide mounted on a bed 62^a. A detail is shown in Fig. 8. After the spool reaches the discharging position shown at the lower right hand corner of Fig. 1, the slide may be moved inwardly, so that the cradle portions 62^b will be disposed beneath the flanges of 130

the spool, in this instance the loaded spool E². The slide is provided with a spring-actuated latch 62^a, suitably recessed to engage one of the flanges of the spool, so that the 5 spool will be withdrawn with the slide when the slide is retracted. The latching member 62^a is provided with suitably beveled surfaces, so that it will snap automatically into engagement with the flange of the spool, as 10 will be readily understood from Fig. 8. The slide 62 is equipped with a bottom guide plate 63, secured by screw and sleeve connections 64 to the main body of the slide. The guide plate 63 works beneath shoulders 64^a 15 with which the bed 62^a is provided, so that the slide will not tilt when it is in the spool-receiving position shown in Fig. 8. Normally, the slide is retracted when the machine is 20 in operation.

As shown in Fig. 1, a platform, truck or carriage 65 is disposed adjacent the slide 62, so that after the slide has been withdrawn with the loaded spool thereon, the 25 spool may be rolled on to the truck or carriage.

The spools may be held in position on the spindle by any suitable means. In the illustration given, the ends of the spindles are threaded and equipped with nuts 66 (Fig. 30 2). When it is desired to remove a loaded spool, the nut may be removed from the spindle after the slide 62 has been moved into position to receive the spool, and the slide 62 may then be withdrawn, carrying 35 with it the loaded spool.

The operation of the machine is as follows:

The machine is actuated through the medium of the gear M² on the shaft M, it being 40 understood that the gear M' drives the spindle-gears H continuously, but that the spindle-gears are not clutched to their spindles so long as the spindles are passing over the large segmental cam T. During the loading 45 of a spool, the carrier occupies the position illustrated in Fig. 1. In this position, the spool D² is in the loading position, the spool E² is in the discharging position, the spool F² is about to be applied to the spindle, and 50 the spool G² is in the "ready" position. In this position, the spool D² is rotated to wind the wire 3 thereon as it is discharged from the self-discharging capstan A. It will be noted in Fig. 1 that the wire passes substantially tangentially to that spool which is 55 in the loading position. The friction clutch employed in connection with the spindle may be so adjusted as to permit slippage of the spindle with respect to the spindle-gear. 60 The adjustment may be such as to give the desired tautness to the wire, but it is unnecessary to place a drawing strain upon the wire, owing to the fact that the self-discharging capstan will continue to pay out

the wire, regardless of whether it is wound immediately on to the spool or not.

The control mechanism R operates continuously, and so the cam segment 37^b moves continuously, thus serving to actuate the distributor so long as the spool is in the loading position. Also, through the medium of the rock member which comprises the arms 40^a and 40^b, the link 54 is continuously reciprocated, thereby causing the pawl 53 to 70 actuate the ratchet wheel 50. When the spool has received the requisite number of turns, the cam stud 57 on the ratchet wheel actuates the rock-lever 56, thereby permitting the link 55 to drop, so that the slide 45 will be actuated. When the slide 45 is 75 actuated, it depresses the rear end of the rock-lever 43, lifts the cam link 42, and allows the sliding key 41 to engage the notch 41^a of the sleeve 33. This causes the carrier-actuating gear 30^a to operate and turn the carrier. 80 The moment after the carrier starts to turn, the clutch of the spindle of the loaded spool is released, so that the loaded spool ceases to rotate. Simultaneously therewith, the clutch of the spindle of the "ready" spool operates 85 by reason of the fact that the controlling plunger rides off of the cam T. For a very short period two spools are rotating. When the cam stud 28 of the distributor comes within the control of the cam slot 58 of the cam S, the distributor slide is given an extra movement, and thus the wire is deflected over the peripheries of the face plates of 90 the two rotating spindles, and the grippers on the face plates engage the wire at both sides of the cutter. Practically simultaneously therewith, the cutter operates to 95 sever the wire. The carrier continues to rotate until the "ready" spool is brought to the loading position and the loaded spool is 100 brought to the discharging position. The control mechanism operates to return the cam link 42 to the position shown in Fig. 4, thus disconnecting the shaft of the carrier-actuating gear 30^a from the sleeve 33 at the 105 proper moment.

The cam lug 37^a is so located that it will 110 actuate the arm 40^a while the slide 38 is in the position shown in Fig. 3. At this point, the distributor I is locked by the ball lock 115 26, and thus the cam stud 28 is in such position that when the carrier is rotated, said cam stud will pass from the fork 38^b (Fig. 5) to the slot 58 of the stationary cam S, so that the distributor will be given the 120 extra movement illustrated in Fig. 5.

In the illustration given, four spindles are employed, and the carrier has a movement of 90 degrees between each spool-loading operation. Any desired number of spindles may 125 be employed, however.

It will be noted that the control mechanism operates periodically to cause the step-

- by-step movement of the carrier; also, that the rotation of the carrier, in connection with the operation of the interrupted cam T, controls the operation of the spindles.
- 5 Thus, the machine is wholly automatic in its operation, except as to the removal of the loaded spool after it reaches the discharging position and the applying of a fresh spool to the spindle at the next position.
- 10 A machine of the character described is well adapted to the purpose of taking up, reeling, or spooling comparatively heavy gage wire, where the weight of the wire may ordinarily range from 50 pounds to 250
- 15 pounds per spool. The empty spool is easily handled and may be applied with ease by an attendant watching the operation of the machine.

The feature of the self-discharging capstan employed in combination with take-up mechanism of the general character described, is of very great importance. The self-discharging capstan operates to draw wire continuously from the finishing die and 20 discharge the wire from itself without the need of a drawing tension between the capstan and the take-up mechanism. Thus, the drawing tension upon the wire need never be varied, and so not only is a continuous 25 drawing operation of the wire rendered possible, but breakage is obviated. Thus, the improved machine is capable of a large output, loss of time from stopping of the machine is avoided, and still heavier losses of 30 time from breakage of wire are avoided. Those skilled in the art will readily appreciate the advantage, inasmuch as the troublesome threading of the wire through the dies of the drawing machine is largely avoided.

35 The continuity of the drawing operation is therefore made to depend upon the life of the die, or upon the length of rod or wire which is available; and inasmuch as it is possible to weld rods together successfully 40 for drawing purposes, the ultimate length of continuous operation may be made to depend practically altogether upon the life of the die.

It may be added that the slippage provided for between the spindles and their gears will compensate for an increase in diameter of the coil being wound on the spool and will also compensate for any slight variations which may occur in the operation of 50 the take-up mechanism, the self-discharging capstan operating at all times to exert a continuous drawing tension upon the wire as it passes through the dies.

The tautness with which the wire may be 60 wound upon the spool or reel may be varied by regulating the tension at the friction clutches of the spindle-gears. If it be desired to remove the wire in coils, this may be effected by employing any suitable core or mandrel in lieu of the spool, so that the

coil of wire may be slipped off the core when the core is brought to the discharging position. For the heaviest sizes of wires, there is always a sufficient period between movements of the carrier to enable the coil or loaded spool to be removed and to enable a fresh spool to be applied.

70 The foregoing detailed description has been given for clearness of understanding only, and no unnecessary limitations should be understood therefrom, but the appended claims should be construed as broadly as permissible in view of the prior art.

75 What we regard as new, and desire to secure by Letters Patent, is:

1. In combination, a self-discharging capstan operative to deliver a continuous strand, and take-up mechanism for winding said strand in a plurality of coils, said take-up mechanism comprising a carrier, a plurality of spindles mounted on said carrier, and means for automatically connecting the wire with said spindles, in turn.

80 2. In combination, a self-discharging capstan operative to deliver a continuous strand and having associated therewith means for applying pressure to convolutions upon said capstan, and take-up mechanism for winding said strand in a plurality of coils, said take-up mechanism comprising a carrier, spindles mounted on said carrier and moving in an endless path, wire-gripping means associated with each spindle, wire-distributing means co-acting with the several spindles, and wire-severing means.

85 3. In combination, a self-discharging capstan having pressure means associated therewith, a rotatable carrier, a plurality of spindles mounted on said carrier and adapted to be moved thereby in an endless path, wire-gripping means associated with each spindle, wire-distributing means co-acting with the several spindles, means for automatically moving the carrier periodically, and wire-severing means.

90 4. In combination, a self-discharging capstan and associated pressure means, a rotatable carrier, a plurality of spindles mounted on said carrier and adapted to be carried thereby in an endless path, means for successively throwing said spindles into operation, means for automatically actuating said carrier periodically, and means associated with the several spindles for gripping the strand delivered from said capstan.

95 5. In combination, a self-discharging capstan, a carrier, a plurality of spindles mounted thereon and carried thereby in an endless path, means for successively throwing said spindles into operation, means for automatically connecting with said spindles the strand delivered from said capstan, means for severing the strand, and means for automatically actuating said carrier periodically.

6. In combination, a self-discharging capstan and associated presser means, and take-up mechanism comprising a carrier, a plurality of spindles mounted thereon and carried thereby in an endless path, spindle-actuating means mounted in said carrier, means operative during the actuation of said carrier for throwing said spindles successively into operation, carrier actuating means, automatic-control mechanism controlling the operation of the carrier-actuating means, means for automatically connecting with each spindle, in turn, the strand delivered from said capstan, and means for automatically severing the strand. 70
7. In combination, a self-discharging capstan and associated presser means, and take-up mechanism comprising a rotary carrier, carrier-actuating means, a plurality of spindles mounted in said carrier, spindle-driving means mounted in said carrier, clutch devices adapted to drive the spindle and permit slippage of the spindles with respect to the driving means, means for automatically connecting with each spindle, in turn, the strand discharged from said capstan, distributing means, and automatic control mechanism controlling the operation of the carrier-actuating means. 75
8. In mechanism of the character set forth, the combination of a carrier, spindles mounted thereon, a gear device for driving said spindles, spindle-gears driven by said device, a clutch associated with each spindle-gear, a cam controlling the operation of said clutches, carrier actuating means, and control mechanism controlling the operation of the carrier actuating means. 80
9. In mechanism of the character set forth, the combination of a rotatable carrier, a plurality of spindles mounted thereon, a driving device for said spindles, spindle-gears mounted on said spindles and actuated by said driving device, a clutch associated with each spindle-gear, each clutch being provided with a controlling member, a stationary cam co-acting with the controlling members of said clutches, carrier actuating means, and control mechanism controlling the operation of the carrier actuating means. 85
10. In mechanism of the character set forth, the combination of a rotary carrier, a plurality of spindles equipped with spools, spindle-driving means, gears on said spindles actuated by said driving means, means being provided to permit slippage between the spools and said driving means, carrier actuating means equipped with a clutch, and control mechanism controlling the operation of the clutch of said carrier actuating means. 90
11. In mechanism of the character set forth, the combination of a main frame, a rotary carrier, a plurality of spindles carried by said carrier, spindle-gears mounted on said spindles and equipped with clutch
- devices provided with clutch controlling members, a drive-gear serving to continuously rotate said spindle-gears, a segmental cam carried by the main frame and co-acting with said clutch controlling members, and carrier actuating means. 95
12. In mechanism of the character set forth, the combination of a main frame, a rotary carrier, a plurality of spindles carried by said carrier, spindle-gears mounted on said spindles and equipped with clutch controlling members, a drive-gear serving to continuously rotate said spindle-gears, a segmental cam carried by the main frame and co-acting with said clutch controlling members, carrier actuating means, and control mechanism controlling the operation of said carrier actuating means. 100
13. In mechanism of the character set forth, the combination of a main frame, a carrier rotatably mounted therein, a plurality of spindles journaled in said carrier, spindle-gears and associated clutch devices mounted on said spindles, said clutch devices being provided with clutch controlling members, a segmental cam mounted on the main frame and co-acting with said clutch controlling members, said cam being interrupted to permit the spindles to be thrown successively into operation as the carrier is advanced step by step, a gear secured to said carrier, a carrier actuating gear serving to actuate the carrier through the medium of said last mentioned gear, and control mechanism serving periodically to actuate said carrier actuating gear and thus periodically advance the carrier. 105
14. In mechanism of the character set forth, the combination of a self-discharging capstan equipped with a presser-device, a carrier, a plurality of spindles journaled therein, a wire distributor, means for driving the spindles, means for periodically actuating the carrier, and wire-severing means. 110
15. In mechanism of the character set forth, the combination of a carrier, a plurality of spindles journaled therein and adapted to receive spools, a wire distributing device, means for actuating said device, automatic means for actuating the carrier to bring the spools, in turn, to a loading position, means for throwing the spindles into and out of operation, and means for severing the wire after the loading of each spool. 115
16. In mechanism of the character set forth, the combination of a carrier, a plurality of spindles journaled therein and adapted to receive spools, wire distributing means, actuating means for the wire distributing means, wire-grippers associated with the spools, means for giving to the wire distributor an additional movement during the actuation of the carrier, and carrier actuating means. 120
17. In mechanism of the character set forth, the combination of a carrier, a plurality of spindles journaled therein and adapted to receive spools, wire distributing means, actuating means for the wire distributing means, wire-grippers associated with the spools, means for giving to the wire distributor an additional movement during the actuation of the carrier, and carrier actuating means. 125
18. In mechanism of the character set forth, the combination of a carrier, a plurality of spindles journaled therein and adapted to receive spools, wire distributing means, actuating means for the wire distributing means, wire-grippers associated with the spools, means for giving to the wire distributor an additional movement during the actuation of the carrier, and carrier actuating means. 130

17. In mechanism of the character set forth, the combination of a carrier, a plurality of spindles journaled therein and adapted to receive spools, wire distributing means, actuating means for the wire distributing means, wire-grippers associated with the spools, means for giving to the wire distributor an additional movement during the actuation of the carrier, wire severing means, and carrier actuating means.

18. In mechanism of the character set forth, the combination of a rotary carrier, a plurality of spindles journaled therein and equipped with face plates and beyond said 15 face plates with spool-receiving arbors, wire-grippers mounted on said face plates, a wire distributor mounted on the carrier and corresponding with each spindle, means for reciprocating the distributor, in turn, to effect 20 the normal distribution of the wire on the spool, means for effecting additional movement of the distributor during the actuation of the carrier to deflect the wire and bring it within range of the grippers, and carrier 25 actuating means.

19. In mechanism of the character set forth, the combination of a rotary carrier, a plurality of spindles journaled therein and equipped with face plates and beyond said 30 face plates with spool-receiving arbors, wire-grippers mounted on said face plates, a wire distributor mounted on the carrier and corresponding with each spindle, means for reciprocating the distributor, in turn, to effect 35 the normal distribution of the wire on the spool, means for effecting additional movement of the distributor during the actuation of the carrier to deflect the wire and bring it within range of the grippers, wire severing 40 means associated with each distributor, and carrier actuating means.

20. In mechanism of the character set forth, the combination of a carrier, a plurality of spool-carrying spindles journaled in 45 said carrier, said carrier being adapted to bring the spools, in turn, to the winding position, wire gripping means associated with each spindle, wire distributing means, means for effecting deflection of the wire to bring 50 it within range of the grippers after the loading of each spool, means for driving the spindles, and means for actuating the carrier.

21. In mechanism of the character set 55 forth, the combination of a rotary carrier, a plurality of spindles journaled therein, means for actuating said spindles in turn, wire distributing means, wire-grippers associated with each spindle, means for bringing 60 the wire within the range of said grippers during actuation of the carrier, and means for periodically moving the carrier through an angle corresponding with the angle between spindles.

65 22. In mechanism of the character set

forth, the combination of a rotary carrier, a plurality of spindles journaled therein, means for actuating said spindles in turn, a distributor mounted in the carrier and corresponding with each of the spindles, each distributor being provided with an actuating member, a reciprocating member adapted to engage the actuating member of each distributor, in turn, and effect normal reciprocation of the distributor, a stationary cam 75 adapted to engage the actuating member of each distributor, in turn, during rotation of the carrier, and mechanism serving to periodically rotate the carrier through an angle corresponding with the angle separating the 80 spindles.

23. In mechanism of the character set forth, the combination of a rotatable carrier, a plurality of spindles journaled therein, spindle-gears mounted on said spindles, 85 a clutch device associated with each spindle-gear and provided with adjusting means, a clutch controlling member associated with each clutch device, means co-acting with the clutch controlling members adapted to hold 90 each clutch device in the released position during a portion of the rotation of the carrier, a driving gear serving to continuously rotate the spindle-gears, carrier actuating means, and control mechanism controlling 95 the operation of the carrier actuating means.

24. In combination, a self-discharging capstan operative to deliver a continuous strand, and take-up mechanism for winding said strand into a plurality of coils, comprising a rotary carrier provided with a horizontal axis, a plurality of horizontal spindles journaled in said carrier and projecting beyond one side thereof, means for effecting movement of the carrier to bring 105 each spindle, in turn, to loading position, means associated with each spindle for gripping the strand delivered from said capstan, a distributor co-acting with the several spindles, means for operating the spindles, and 110 automatic means for actuating the carrier periodically.

25. In mechanism of the character set forth, the combination of a carrier, a plurality of spindles journaled in said carrier, 115 one of said spindles being located in loading position and another spindle being located in a position ready to be swung to the loading position, a wire distributor mounted in said carrier in the angle between said spindles, wire-grippers associated with said spindles, means for effecting normal oscillation of the wire distributor, means for effecting additional movement of the wire distributor to deflect the wire and bring it within range 120 of the grippers, means for driving said spindles, and means for intermittently actuating said carrier.

26. In mechanism of the character set forth, the combination of a carrier, a plural-

ity of spindles journaled in said carrier, one of said spindles being located in loading position and another spindle being located in a position ready to be swung to the loading position, a wire distributor mounted in said carrier in the angle between said spindles, wire-grippers associated with said spindles, means for effecting normal oscillation of the wire distributor, means for effecting additional movement of the wire distributor to deflect the wire and bring it within range of the grippers, means for driving said spindles, means for effecting severance of the wire after deflection thereof, and means for intermittently actuating said carrier.

27. In mechanism of the character set forth, the combination of a main frame, a rotary carrier mounted thereon, a plurality of spindles journaled in said carrier, means for actuating said spindles, a gear secured to the carrier, a carrier actuating gear serving to actuate the carrier through the medium of said last mentioned gear, and control mechanism including a continuously rotating member, a clutch device for connecting the carrier actuating gear to said continuously rotating member, and a controlling device for said clutch periodically actuated by said control mechanism.

28. In mechanism of the character set forth, the combination of a main frame, a rotary carrier mounted thereon, a plurality of spindles journaled in said carrier, means for actuating said spindles, a gear secured to the carrier, a carrier actuating gear serving to actuate the carrier through the medium of said last mentioned gear, and control mechanism comprising a continuously rotating member, a clutch device for connecting said continuously rotating member to said carrier actuating gear, a clutch controlling member controlling the operation of said clutch device, and a ratchet wheel driven from said continuously rotating member and controlling the actuation of said clutch controlling member.

29. In mechanism of the character set forth, the combination of a main frame, a carrier journaled therein, a plurality of spindles journaled in said carrier, means for actuating said spindles, in turn, a gear secured to said carrier, and control mechanism mounted on the main frame, comprising a carrier actuating gear adapted to communicate motion to the gear secured to said carrier, a clutch device controlling the operation of the carrier actuating gear, and a continuously operating control device mounted on the main frame and controlling the operation of said clutch device.

30. In mechanism of the character set forth, the combination of a main frame, a rotary carrier journaled therein, a plurality of spindles journaled in said carrier, means for actuating said spindles, a plurality of

wire distributors mounted in said carrier, a distributor actuator mounted on the main frame and adapted to actuate said distributors, in turn, a gear secured to said carrier, and control mechanism comprising a gear journaled on the main frame and serving to actuate the gear secured to said carrier, a continuously rotating member, a clutch device adapted to connect said carrier actuating gear to said continuously rotating member, a continuously driven cam adapted to effect normal reciprocation of the distributors, in turn, a ratchet device actuated from said cam member, a clutch controlling member controlled by said ratchet device, and a stationary cam mounted on the main frame and serving to deflect the wire during actuation of said carrier.

31. In mechanism of the character set forth, the combination of a main frame, a carrier journaled therein, means for intermittently actuating said carrier, a plurality of spindles journaled in said carrier and equipped outside said carrier with face plates provided with grippers, and having arbors projecting beyond said face plates, means for actuating said spindles, and means for effecting distribution of the wire during the loading operation and for effecting deflection of the wire to bring the same within range of the grippers.

32. In mechanism of the character set forth, the combination of a main frame, a carrier mounted therein, a plurality of spindles mounted in said carrier and equipped with face plates disposed outside of the carrier and having arbors projecting beyond the face plates, said face plates being equipped with grippers, means for actuating said spindles, means for periodically actuating the carrier, and means for effecting removal of the load after the carrier has been rotated to bring a fresh arbor to the loading position.

33. In mechanism of the character set forth, the combination of a main frame, a rotary carrier journaled therein, a plurality of spindles journaled in said carrier and having arbors projecting in front of the carrier, means for actuating said spindles, in turn, means for intermittently actuating said carrier, and a load removing carriage adapted to receive the load after the carrier has been actuated to bring a fresh spindle to the loading position.

34. The method of spooling wire or the like which comprises progressively forming convolutions upon and progressively discharging the wire from a self-discharging winding drum, passing the wire, or the like, as discharged to take-up mechanism equipped with a plurality of spools, filling each spool, in turn, and shifting the spools to bring a fresh spool to the loading position.

35. The method of spooling wire which comprises progressively forming convolutions upon and progressively discharging the wire from a self-discharging winding drum, winding the wire upon a spool until the spool is loaded, and shifting the loaded spool and bringing a fresh spool into the loading position.

36. The method of spooling wire which
10 comprises progressively forming convolu-

tions upon and progressively discharging the wire from a self-discharging winding drum, winding the discharged wire upon a spool until the same is loaded, shifting the loaded spool and bringing a fresh spool to the loading position, deflecting the wire between said spools, and severing the wire and securing the ends.
